UNITED STATES PATENT OFFICE.

ALONZO A. WARNER, OF NEW BRITAIN, CONNECTICUT, ASSIGNOR TO LANDERS, FRARY AND CLARK, OF NEW BRITAIN, CONNECTICUT, A CORPORATION.

MEAT-CUTTER.

No. 908,714.

Specification of Letters Patent.

Patented Jan. 5, 1909.

Application filed February 5, 1908. Serial No. 414,380.

To all whom it may concern:

Be it known that I, ALONZO A. WARNER, a citizen of the United States, residing at New Britain, in the county of Hartford and 5 State of Connecticut, have invented certain new and useful Improvements in Meat-Cutters, of which the following is a specification.

My invention relates to improvements in 10 meat cutters, and the objects of my improvement are convenience in assembling the parts with efficiency when assembled, efficiency in the forcing means, and to provide means for cleaning the threads of the 15 case and clamp ring at the delivery end of the case.

In the accompanying drawing: Figure 1, 20 is a sectional view of parts of my meat cutter on the line *x-x* of Fig. 2, other parts being shown in elevation. Fig. 2 is an end view of the delivery end of the same with the clamp ring, perforated plate and knife removed. Fig. 3 is a sectional view of the clamp ring on the line *s-s* of Fig. 1. Fig. 4 25 is a sectional view of the same on the line *y-y* of Fig. 3, and—Fig. 5 is a face view of the rotary knife.

A, designates the frame having at one end a tubular bearing 6 for the crank shaft 7, to 30 one end of which shaft the crank 8 is secured in any ordinary manner and on the other end of which shaft the smaller gear wheel or pinion 9 is mounted. The case *B* is mainly cylindrical and provided with the 35 usual hopper 10 at or near its receiving end and also with a standard 11 which is received in a socket 12 at the other end of the frame *A*, and is held therein by means of the screw 13, thereby properly locating the case 40 in position relatively to the crank shaft and parts mounted thereon.

The interior of the cylindrical body of the case is provided with straight longitudinal feeding ribs 14. The delivery end of the 45 case is enlarged to receive an ordinary perforated plate 15 which is held in place against working outwardly by means of the internally threaded clamp ring 16 that is screwed upon the externally threaded portion 17 at the threaded end of the case. The 50 said case is provided at its hopper end with a tubular shaft bearing or hollow boss 18.

The screw or forcer *C* is provided at its 55 delivery end with an oblong squared portion 19 to receive the rotary knife 20 that bears

on the inner face of the perforated plate 15 in the ordinary manner, the hub of the said knife having an oblong square hole 21, Fig. 5, to fit on the like squared portion 19 of the forcer. The said forcer also has at its outer 60 end a journal pin or shaft like portion 22 that is received in a central bearing of the perforated plate in the ordinary manner of similar meat cutters. The hopper end of the forcer has a shaft like portion which is divided into three parts, viz: a larger cylindrical portion 23, a smaller cylindrical portion 24 and an intermediate squared or angular portion 25. The larger cylindrical portion extends through the perforated boss or bearing 18 of the case and projects a little therefrom when this end of the forcer is passed endwise therethrough from within the case. This projecting portion with the squared portion and smaller cylindrical portion receive 75 and center the larger and detachable gear wheel 26 which as shown is an internal gear that is driven by the smaller gear or pinion 9. The axial bore or hole through the hub 27 of this detachable gear 26 is of a shape and size 80 at its respective parts to fit these three divisions or parts of the said shaft, and is also provided with a set screw 28 that impinges upon the squared portion 25 of the shaft to hold the larger gear in place. It is necessary 85 to remove or loosen the larger gear wheel from that end of the forcer before the forcer can be withdrawn from the case and it is essential that when in place it must not only be secured against rotating independently of 90 the shaft but must be held centrally and squarely thereon in order to have this removable gear properly engage the teeth of the driving gear 9. The squared portion 25 of the forcer shaft in connection with the interior squared portion of the hub 27, hold the 95 said gear against rotation, while the two cylindrical portions 23 and 24 on either side of the said squared portion, center the gear 26 properly, and also hold it squarely to the 100 axis of the forcer so that the set screw 28 cannot displace it from this correct position, even if the squared portion does not exactly fit the interior of the hub. It is always a difficult matter to make such squared portions fit nicely, but with a cylindrical portion at either side or end of the squared portion, the removable gear is always correctly placed whether the squared portion is fitted 105 nicely or otherwise. The body of the forcer, 110

that is its feeding screw portion which works within the case, differs from ordinary forceers by having what may be called a ratchet thread, that is to say the bottom 29 of the 5 thread 30 within the cylindrical portion of the case is nearer to the said thread on that side of the thread which is nearest the delivery end of the case than it is to the opposite side of the thread. At the hopper end, 10 or under the hopper, the thread is or may be of the ordinary construction. Making the thread of the forceer widest on one side in the direction described makes the forward side of the forceer thread longer than usual and I 15 prefer to make it nearly of a straight taper standing at an acute angle to the axis of the forceer so as to force the meat out radially against the feeding ribs whereby the efficiency of the feed is increased. The widest 20 part of the thread is on that side which faces the delivery end of the case and the opposite or narrow side stands at an obtuse angle to the axis of the forceer. This efficiency of the feed is best maintained by straight longitudinal feeding ribs and a case body that is 25 of uniform diameter from the hopper to the delivery end.

By making the internal diameter of the body of the case the same from end to end, 30 the volume of the material passing therethrough neither increases nor decreases at different points in the length of the case, and thus the feed is uniform and the material does not work outwardly away from the 35 feeding ribs, as it does in a case that enlarges towards the delivery end.

The delivery end of the case and the clamp ring or nut are propided with one or more recesses that cut through a part of the 40 threads similar to the grooves of a screw cutting tap. As shown, I form three recesses 31 in the outer thread 17 of the case B and three like recesses 32 in the inner threads of the nut or clamping ring 16, so as to cut through 45 a part of the threads, both on the case and in the nut to present the ends of the broken threads to the recess, care being taken to leave the outer thread or threads of each unbroken so that the meat which gathers 50 around the outer edge of the perforated plate within the clamping ring will be retained therein by the unbroken threads. At the same time the meat that generally finds its way to a greater or less extent into the 55 grooves of the threads will be cleaned out of the said grooves by the act of unscrewing the nut or clamp ring. The same effect or result will be accomplished to some extent by making such recesses or breaks in the threads of one 60 of the said parts, although it is better to have broken threads in both. The ends of the threads in the recesses of one part act as cutters to clean the meat out of the threads on the other part.

65 The perforated plate is prevented from ro-

tating by the ordinary stud 33 in the case and a notch 34 in the edge of the said plate to receive the said stud.

I claim as my invention:

1. In a meat cutter having a case, provided with screw threads at its delivery end, a perforated plate and a threaded clamp ring for screwing on the threaded end of the case and holding the said plate, the said threaded end having a part of the threads cut through 75 by recesses to form broken threads with the ends of the broken threads in the recesses of one part, for cleaning the grooves between the threads of the other part, substantially as described.

2. In a meat cutter having a case threaded at its outer end, a perforated plate and a threaded clamp ring for holding the said plate at the end of the case, the threaded end of the case having its outer threads broken 85 by recesses cutting through the said threads, while the remaining threads farthest from the said outer end are unbroken.

3. In a meat cutter having a case threaded at its outer end, a perforated plate and a 90 threaded clamp ring for holding the said plate at the end of the case, the inner threads of the clamp ring being broken by recesses cutting across the said threads, while the outer one of the threads on the said clamp ring is unbroken.

4. In a meat cutter having a case threaded at its outer end, a perforated plate and a threaded clamp ring for holding the said plate at the end of the case, the threaded end of the case having its outer threads broken 100 by recesses cutting through the said threads while the remaining threads are unbroken, and the said clamp ring having its inner threads broken by recesses cutting across the 105 said threads while the outer one of its threads is unbroken.

5. In a meat cutter, a case having a receiving hopper at one end, a perforated plate at its delivery end, a cylindrical body portion of 110 uniform diameter from the said hopper to the said delivery end and straight feeding ribs extending longitudinally of the said body portion; and a screw forceer mounted to rotate within the said case, that part of 115 the said forceer which is within the said cylindrical body portion having a thread that is widest on that side which faces the said delivery end and narrowest on its opposite side, the said widest side tapering from the bottom of the thread outwardly at a sharp angle of less than forty five degrees to the axis of the forceer, and the opposite and narrower side of the said thread extending outwardly at a blunt angle of more than fifty degrees to 125 the said axis.

6. In a meat cutter having a case, with a tubular shaft bearing at one end, a screw forceer having a body for rotating within the said case and a shaft like portion at one end 130

adapted to be passed endwise through the said bearing from within the case, the said shaft like portion being divided into three parts, a larger cylindrical part fitting the 5 said tubular bearing and projecting therefrom a smaller cylindrical part at the outer end of the said shaft like portion and a squared portion intermediate the said two cylindrical portions; and a detachable gear 10 wheel having a hub with an axial hole therethrough, the said hole being fitted to the said three divisions of the shaft like portion of the said forcer, and the said hub having also a set screw for impinging against the said intermediate squared portion, substantially as 15 described.

7. In a meat cutter, a frame having a socket for a standard at one end, and a bearing for a crank shaft at its opposite end, a 20 crank shaft mounted in said bearing and having a crank at one end and a driving gear at its other end, a cylindrical case having a tubular shaft bearing at one end and a stand-

ard fitted to the socket of the said frame, a screw forcer having a body for rotating with- 25 in the said case and a shaft like portion at one end of the said body adapted to be passed endwise through the said tubular bearing from within the case, the said shaft like portion having three divisions, a larger 30 cylindrical portion, a smaller cylindrical portion and a squared portion between the two, a detachable gear having a hub with an axial hole therethrough which is fitted to the said three divisions of the said forcer shaft, the 35 said hub having also a set screw for impinging against one of the sides of the said squared portion and the said detachable gear when thus mounted on the said forcer shaft being in engagement with the driving gear 40 of the crank shaft for being driven thereby.

ALONZO A. WARNER.
